UNITED STATES PATENT OFFICE.

LEONARD VYNE, OF NORTHWILKESBORO, NORTH CAROLINA.

DEVICE FOR FORMING BELT-LACINGS.

No. 891,884.

Specification of Letters Patent.

Patented June 30, 1908.

Application filed August 31, 1907. Serial No. 390,989.

To all whom it may concern:

Be it known that I, LEONARD VYNE, a citizen of the United States, residing at Northwilkesboro, in the county of Wilkes and State 5 of North Carolina, have invented a new and useful Device for Forming Belt-Lacings, of which the following is a specification.

This invention relates to a device for forming belt lacings, and is designed as an improvement upon an article of this character 10 for which I secured Letters-Patent of the United States dated October 11, 1898, No. 612,070.

The object of the present invention is to 15 improve and simplify the construction of the device illustrated in said patent by dispensing with the employment of the locking pin around which the wire is passed, and the eyes or loops for receiving the locking pin, and in 20 lieu thereof to employ hooked members that shall secure the same results as the locking pin and the eyes but will materially simplify the device and expedite the procedure of forming the lacing members.

With the above and other objects in view 25 as will appear as the nature of the invention is better understood, the same consists in the novel construction and combination of parts of a device for forming belt lacings, as will be 30 hereinafter fully described and claimed.

In the accompanying drawings forming a part of this specification and in which like characters of reference indicate corresponding parts,—Figure 1 is a view in side elevation 35 of a wire crimping device constructed in accordance with the present invention. Fig. 2 is a top plan view of a portion thereof. Fig. 3 is a transverse sectional view taken on the line 3—3 of Fig. 1.

Referring to the drawings, 1 designates a supporting frame or bar, which may be of any suitable material, preferably of wood, and secured to the opposite sides of which, by bolts 2 and nuts 3, are the crimping members 4 and 5. Each of these members is constructed of a bar or strip of metal, of any suitable thickness. The upper edge of the member 4 is provided with hooks 6, the forward walls of which are curved and the upper and rear walls of which are straight, the 45 general contour of the bills of the hooks being

such as to facilitate the disconnection therefrom of the wire being kinked or crimped or bent. The member 5 is provided on its upper edge with rectangular tongues 7 which are equal in number to the hooks and are disposed 55 in break-joint order relatively thereto,—that is to say, the terminals of the bills of the hooks will be disposed approximately in transverse alinement with the medial lines of 60 the tongues. The tongues, as shown in Fig. 1, are longer than the hooks in order to facilitate the bending of the wire therearound.

In forming the lacing with this implement, one end of the wire is suitably held against 65 slipping, is then looped around one of the tongues 7, thence passed across the stock and beneath the adjacent or alined hook, thence over the same, thence around the next succeeding tongue, and so on throughout the 70 series of tongues and hooks. When the complete length of lacing is completed, the loops may readily be detached from the hooks and tongues.

The improvements herein defined are simple in character and will be found thoroughly 75 efficient for the purposes designed and will materially simplify the construction of the article and thus measurably reduce the cost of its manufacture.

What is claimed is:—

An article of the class described, comprising a bar, and plates secured on the opposite sides thereof, one of which is provided with longitudinally disposed equally spaced 85 rectangular tongues, and the other with a like number of longitudinally disposed equally spaced incurved hooks, the bills of which are at their upper ends, thus to facilitate detachment of the wire therefrom, the 90 spaces between the tongues and the hooks all opening in the same direction, and the terminals of the bills of the hooks being disposed approximately in transverse alinement with the medial lines of the tongues. 95

In testimony that I claim the foregoing as my own, I have hereto affixed my signature in the presence of two witnesses.

LEONARD VYNE.
